UNITED STATES PATENT OFFICE.

WALKER GETCHELL, OF BATH, MAINE.

IMPROVEMENT IN COMBINED WARDROBES, BEDSTEADS, CHAIRS, AND TABLES.

Specification forming part of Letters Patent No. 142,387, dated September 2, 1873; application filed February 15, 1873.

To all whom it may concern:

Be it known that I, WALKER GETCHELL, of Bath, in the county of Sagadahoc and State of Maine, have invented a new and Improved Combination Cabinet, of which the following is a specification:

The invention consists in the improvement of cabinet articles, as hereinafter described and pointed out in the claim.

Figure 1 is a side elevation of the combination-cabinet article complete in the folded-up condition. Fig. 2 is a longitudinal sectional elevation of the bed, lounge, or inverted reclining-chair. Fig. 3 is a plan view of Fig. 2, with a part of the bottom broken out. Fig. 4 is an inside elevation of the front portion, which constitutes the table when detached and set up. Fig. 5 is a transverse section of the table; and Fig. 6 represents the chair, which is formed of the several pieces comprising the top of the case.

Similar letters of reference indicate corresponding parts.

A is the front of the cabinet, represented in Fig. 1, with narrow sides B forming parts of the sides thereof, and constituting the pendent sides of the table-top when detached from the case and arranged for the table, as represented in Fig. 5, the folding-legs C, which are pivoted to it, as represented in Fig. 4, being let down and fastened by the buttons D. The part E of the top of the cabinet constitutes the back of the chair, Fig. 6, and has the seat F hinged to it at G. It also has the upholstered cushion H' above the seat, and this is so fitted on the back and connected to the seat that, when it swings down against the side of the back to adjust the latter for its place in the cover, it draws the cushion down below the top to uncover the end sufficiently to rest on the top of the side-board of the cabinet, and when the seat swings up into position it moves the cushion up to hide the back. The sides of the chair are formed of the two boards H, which, being constructed as represented in Fig. 6, nest together so as to be laid on the top of the cabinet and constitute the balance of the cover. These sides hold the seat at the front by the pins I. The sections K and L of the sides of the case, and boards J between the front A B and the main part M, comprise the principal portion of the bed or reclining-couch, K and L being the sides, and J the bottoms. The section K is pivoted at the upper end to the top of L, and L is pivoted to the part M at N, so as to swing down to the positions represented in Fig. 1. A prolongation of the bottom J is formed by the board O, which is pivoted to it at P, so as to swing up and down, and it is connected to arms Q, which extend along under L, and at their extremities are connected by cords R to a roller, S, with a holding-pawl for raising and lowering the head-support and holding it at any point. This piece folds up vertically against the bottom J when the sections K L are folded up, and, as it is wider than the distance from the hinges P to the top, it is jointed at T to fold over. The arms Q are jointed at U, so that the lower parts fold up against the bottom J. The legs a of the section K turn up and let the outer end down, as indicated by the dotted lines b, to adjust the apparatus for a reclining-couch, also to lie against the bottom J when the bed is folded up. When the section K is let down for a couch the notches opened between the ends of the sections K and L are closed by the triangular pieces d fitted in them and fastened by hooks and eyes. The notches or spaces between the end of the section L and the front edges of the sides of the part M are fitted up to make a finish by the boards e, which are fastened in by the hooks and eyes f. These pieces d and e are packed against the under side of the table when the cabinet is folded up, and secured by buttons D g h i and some of the legs of the table, as represented in Fig. 4. A' is the washstand, with a towel-rack attached, mounted on a door, B', which is hinged to the side of the part M, where an opening, C', is made in the side of the case into a chamber within, so that the stand swings into the case and is inclosed when the door is shut, and swings out for use when the door is opened. At the side of the part M, opposite the one having the washstand, a drawer, D', is arranged for linen and other like goods. The bed or lounge K L, &c., will be upholstered in any approved way. The rollers S may be turned to wind or unwind the cords by a wrench applied at Y. The pawl y projects above

the roller, where it can be raised when turning the crank, as required.

Having thus described my invention, I claim as new and desire to secure by Letters Patent—

1. A cabinet comprising the table A B C, chair F G H, bed K L J O, and the washstand arranged in one article, substantially in the manner herein described.

2. The arrangement of the chair-back E and sides H, by which they comprise the said parts of the chair and the cover of the cabinet, substantially as specified.

3. The arrangement of the cushion H' and the seat F of the chair with the back, and each other to shift the cushion along the back, substantially as specified.

4. The arrangement of the sections K, L, J, and O of the bed, together with the parts A,

B, and M of the cabinet, substantially as specified.

5. The combination of the head-piece O and jointed arms Q V with the sections K L and the case, substantially as specified.

6. The combination of the roller S with holding devices, and the cords R with the jointed arms Q and head-piece O, substantially as specified.

7. The detachable triangular pieces d combined with the sections K L of the bed, substantially as specified.

8. The combination of the detachable pieces e with the section L and the sides of the part M of the cabinet, substantially as specified.

WALKER GETCHELL.
